(57) **CLAIM**

The ornamental design for a display screen or portion thereof with a graphical user interface, as shown and described.

DESCRIPTION

This patent or application file contains at least one drawing executed in color. Copies of this patent or patent application publication with color drawing(s) will be provided by the Office upon request and payment of the necessary fee.

FIG. 1 is a front view of a first embodiment of a display screen or portion thereof with a graphical user interface.

FIG. 2 is a front view of a second embodiment of a display screen or portion thereof with a graphical user interface.

FIG. 3 is a front view of a third embodiment of a display screen or portion thereof with a graphical user interface.

FIG. 4 is a front view of a fourth embodiment of a display screen or portion thereof with a graphical user interface; and,

FIG. 5 is a front view of a fifth embodiment of a display screen or portion thereof with a graphical user interface.

The broken lines in the Figures showing the remainder of the graphical user interface and the remainder of the display screen or portion thereof are for environmental purposes only and form no part of the claimed design.

1 Claim, 5 Drawing Sheets
(3 of 5 Drawing Sheet(s) Filed in Color)
